Patented Dec. 29, 1925.

UNITED STATES PATENT OFFICE.

EDWARD H. REMDE, OF CLEVELAND, OHIO, ASSIGNOR TO THE BAKER R. & L. COMPANY, OF CLEVELAND, OHIO, A CORPORATION OF OHIO.

INDUSTRIAL TRUCK.

Application filed October 3, 1922. Serial No. 592,138.

To all whom it may concern:

Be it known that I, EDWARD H. REMDE, a citizen of the United States, residing at Cleveland, in the county of Cuyahoga and State of Ohio, have invented certain new and useful Improvements in and Relating to Industrial Trucks, of which the following is a specification.

This invention relates to an industrial truck, more particularly an industrial truck having an elevating device or platform.

One object of the invention is to provide in a truck of this character improved elevating means for the elevating device or platform, capable of raising and lowering the latter in a rapid and easy manner, whereby loads may be moved vertically and readily transported.

Another object of the invention is to provide in a truck of this character improved elevating means, in which the power to raise and lower the platform is applied without tendency to distort the platform in its guide members while moving vertically.

A further object of the invention is to provide in a truck of this character an improved elevating mechanism in which winding drums are disposed at opposite sides of a centrally arranged driving means and the flexible members or ropes to be wound on and from said drums run over sheaves which are so disposed that the pull or tension on the flexible members or ropes is equalized to effect rectilineal movement of the platform.

Other objects of the invention will be apparent to those skilled in the art to which my invention relates from the following description taken in connection with the accompanying drawings, wherein—

Fig. 1 is a side elevation of a truck embodying my invention.

Fig. 2 is a fragmentary perspective view, enlarged, showing the elevating means.

Fig. 3 is a fragmentary elevation, enlarged, of the motor and power transmitting means between it and the winding drums, partly in section.

Fig. 4 is a section on the line 4—4 of Fig. 3.

In the drawings, 1 indicates as an entirety a frame comprising a main section 2 and a sub-section 3, preferably arranged in a plane below the main section. The main section is preferably constructed as de-

scribed and claimed in my co-pending application, filed November 20, 1920, Serial No. 425,555 Patent No. 1,554,167, dated Sept. 15, 1925. The inner or adjacent ends of the main section 2 and sub-section 3 are preferably connected by a pair of angle members 4, each riveted to the frame members or sections in a well known manner.

The sub-section 3 preferably comprises pairs of parallel members 5. 6 indicates a pair of wheels disposed below and preferably within the sides of the main section 2. The wheels 6 are preferably pivoted to an axle (not shown) by means of knuckle joints in a well known manner, whereby they may be turned for steering purposes. 7 indicates a pair of wheels mounted on an axle (not shown) upon which the sub-section 3 is supported. The wheels 7 are preferably arranged to be swung about a vertical axis or axes for steering purposes, being connected by a link 8 and rod 9 to the steering column 10 for the wheels 6, whereby all four wheels may be simultaneously operated by a turning lever 11. 12 indicates a motor for driving the wheels 6. The motor 12 is operatively connected with the wheels by suitable power transmitting mechanism (not shown). 13 indicates a suitable battery or batteries removably supported on the frame section 2 and arranged to supply current to the motor 12. The batteries 13 may be inclosed in a suitable casing 13'. 14 indicates a controller interposed in and controlling the circuit for the motor 12 in a well known manner, the controller being actuated by a suitable lever 15. 16 indicates a step or base on which the operative stands when operating the truck, the steering lever 11 and the controller handle or lever 15 being arranged within convenient reach for this purpose. 17 indicates a foot pedal for controlling the brake or brakes (not shown) for the truck.

18 indicates a pair of spaced guide members disposed vertically, preferably intermediate the ends of the truck frame 1. In the illustrated embodiment of truck construction the guide members 18 are disposed at the connection of the inner ends of the sections 2, 3, with each other, this arrangement (1) permitting the guide members to be extended to or below the sub-section 3 so that the platform may be lowered to the desired plane and (2) facilitating the rigid

bracing of the guide members in a vertical position. The guide members 18 preferably comprise a pair of I-beams, so that their flanges or side walls may serve as 5 guides for shoes 19 forming a part of an elevating device or movable platform 20, to which reference will later be made. The shoes 19 are preferably arranged within the opposing channels of the I-beams and engage 10 the inner faces of the adjacent flanges thereof. 21 indicates a pair of beams connected at their outer ends to struts 22, disposed at the front or outer end of the main section 2 and supporting a dash 23 and brackets 24, to which the step or base 16 is connected. At their inner ends, the beams 21 are connected to the base portions of the guide members 18 preferably by rivets. 25 indicates a pair of tie rods, each extending 20 from the joint between the adjacent beam 21 and strut 22 to the upper end of the adjacent guide member 18, being preferably secured to the latter by means of an end plate 26 fixed to the guide member and 25 extending laterally therefrom as shown in Fig. 1.

The elevating device or platform 20 comprises a shoe member 27 and a platform member 28 connected thereto. The shoe member 27 preferably comprises a pair of shoes 19, already referred to, connected together by a pair of spaced plates 29 and upper and lower shoe elements 30 carried by each shoe 19 and engaging the inner side walls 35 of the adjacent guide member 18. Each shoe element 30 consists of a roller loosely mounted on a stud shaft 31 supported in the wall of the adjacent shoe 19. The shafts 31 are inclined so that the circumferential 40 surfaces of the rollers may engage the inclined inner surfaces of the side walls of the adjacent guide member 18 without undue friction. As will be understood from Fig. 1, the stud shafts 31 carried by each shoe 19 are inclined at an angle relative to each other and parallel to the faces of the flanges or side walls of the adjacent guide member 18 with which they engage, respectively, so that the lower roller will 45 engage its rear side wall and the upper roller will engage its front side wall. The platform member 28 preferably comprises a pair of spaced arms 28^a extending laterally relative to the shoe member 27 over the sub-section 3 and a plate 28^b disposed on the arms 28^a. The plate may be provided with side walls 28^c and its outer end may extend beyond the arms 28^a. Each of the arms 28^a is provided with a hinge element 28^d correlated with a hinge element at the lower end of the adjacent shoe 19, being connected thereto by pivot pin 28^e which connects the hinge elements of both arms to the shoes, this construction permitting the platform 50 to swing upwardly at its free end.

The parts and elements above described correspond to like parts and elements shown and described in my co-pending application, filed April 14, 1922, Serial No. 552,780, for which reason further description herein 70 is deemed unnecessary.

32 indicates as an entirety the hoisting or elevating mechanism for the elevating device or platform 20. Of this mechanism, 33 indicates a motor, preferably of the electric type, arranged to be supplied with current from the batteries 13 and operated by means of a controller 33'. 34 indicates a supporting member, to which the motor is secured in a well known manner, preferably by cap screws 34^a. The lower portion of the supporting member 34 is shaped to form a housing 34^b for power transmitting means 35. 36 indicates a shaft preferably of sectional character, which is driven by the power means 35, the sections 36^a, 36^b, constituting the shaft 36 extending laterally in opposite directions through the housing 34^b and having connected to their outer end drums 37, 37', to which reference will later be made. 90 As shown in Fig. 3, the housing 34^b is formed in its opposite sides with aligned openings 38, through which the shaft sections 36^a extend. 39 indicates a pair of spaced standards mounted on the frame section 2, preferably near its rear or inner end between the guide members 18 and the battery housing 13', and serving as supporting means for the power transmitting means 35, the supporting member 34 and the motor 33. As shown, the standards 39 are arranged to support the motor 33 with its armature shaft in the central longitudinal plane of the truck frame 2 and the drums 37, 37', at equal distances from and at the opposite sides of that plane. Each standard 39 is preferably provided with front and rear feet, the former being bolted to the rear side wall of the frame 2 or an angle bar 2' carried thereby and the latter being secured to an angle bar 39^a, extending transversely of the frame 2—the upstanding wall of which bar may serve as a stop for the battery housing 13' (see Figs. 1 and 2). At 105 their upper ends, the standards 39 are provided with flanged collars 40, which are in axial alignment with the openings 38 and support sleeves 41, forming shafts for the drums 37, 37', to rotate on. The housing 34^b is secured to the flanges 40' of the collars 40 in any desired manner, for example by bolts 40^a. Each drum 37, 37', is held on the adjacent sleeve 41 by a nut 43, having screw threaded engagement therewith. Each drum 110 is provided with a flange 44 around its inner end. To provide a flange for the outer end of the drum, I secure thereto, preferably by cap screws 45, a round plate 46. The plate 46 has a hub 47, which fits over and is keyed 115 or splined to the outer or free end of the ad-

ja⁵cent shaft section 36^a, such connection serving to transmit the rotary movement of the shaft to the drum. The power means 35 preferably comprise a propeller shaft 35^a, supported in bearings 35^a in the housing 34^b and connected by a suitable joint 35^b with the armature shaft 35^c. The bearings 35^a may be mounted in a section 34^b, which forms a cover for the housing. The cover 10 34^b may be secured in position by screws 34^c. The shaft 35^a is provided with a worm 46', which meshes with a worm gear 47'. The worm gear 47' is preferably secured between the flanges 48, 48', of a pair of annular members 49, 49', respectively, having telescoping collars 50, 50', the inner one of which is keyed to the inner ends of the shaft sections 36^a in a well known way. 51 indicates bearings suitably supported in the 15 housing 34^b and serving to rotatably support the annular members 49, 49'. The upper end of the armature shaft 35^c extends beyond the motor 33 and carries a wheel 52 with which a brake band or shoes 53 may engage to stop the motor and through it the platform 20 and hold the latter in any desired position in which it may be stopped. The brake shoes 53 are connected to an operating lever 53' which is operated to apply 20 the brake by a spring 55 and to release the brake by a solenoid 56, preferably connected in series with the motor 33. 54 indicates a pair of channel bars connecting the upper ends of the guide members 18, being supported upon and secured to flanges 55' provided on the plates 26. 56 indicates hangers disposed between and secured to the channel bars 54. The hangers 56 are provided with suitable bearings 57 which support the opposite ends of a shaft 58. 59, 59', and 60, 60', indicate pairs of sheaves loosely mounted on the shaft 58 and arranged equal distances from a point midway between the guide members 18. 61, 61', indicate a pair of sheaves loosely mounted on a shaft 61^a, supported at its opposite ends in the channel bars 54 and arranged at right angles to the shaft 58 with its axis in a plane midway between the drums, 37, 37'. 62, 62' and 63, 63' indicate pairs of sheaves loosely mounted on shafts 64, 65, respectively, preferably disposed at opposite sides of and equal distances from the plane in which the shaft 61^a is supported and supported at their opposite ends in the plates 29. 66, 66', indicate ropes or other flexible members which run over and around the sheaves and are adapted to be wound on and from the drums 37, 37', to raise and lower the platform 20, together with whatever load is to be carried or transported or moved vertically thereby. The rope 66 extends from the drum 37 over the sheave 59, then around the sheave 62 and then over the sheave 61. From the sheave 61, the rope 66 runs around the sheave 63 and then around the sheave 60, its free end being connected to one end of an equalizing element 67, which is pivoted on a pivot 68, disposed in the plane of the shaft 61^a and supported by a cross bar 68', secured on the guide members 18. The rope 66' extends from the drum 37' over the sheave 60', then around the sheave 63' and then over the sheave 61'. From the sheave 61' the rope 66' runs around the sheave 62' and then over or around the sheave 59', its free end being connected to the opposite end of the equalizing element 67. The operation of winding the ropes on the drums, 37, 37', and 25 30 35 40 45 50 55 60 65 70 75 80 85 90 95 100 105 110 115 120 125 130 unwinding them therefrom to raise and lower the platform will be readily understood. From the foregoing description, it will be seen that the ropes 66, 66', are wound on and off drums which are disposed at opposite sides of the central longitudinal plane of the truck frame, or a point which is midway between the guide members; also that the ropes or cables are carried over sheaves and guided so that the pull thereon incident to raising and lowering the platform and its load is equalized and acts simultaneously through the sheaves carried by the elevating device 20, and the shafts therefor, to operate the platform vertically and in a direction parallel to the guide members 18— thereby eliminating any tendency to pull on or raise or lower one side of the shoe member faster than the other side. As a result, the elevating device or platform 20 is guided freely between the guide members in its vertical movements without undue friction or binding therein or strains on the elevating mechanism. Furthermore, in winding on and from the drums and running around the guide sheaves, the tension in both ropes is the same, so that they (1) operate uniformly in running over and around the latter and (2) wear substantially equally. 69 indicates means for automatically stopping the motor 33 when the elevating device or platform reaches a predetermined position in moving in either direction, certain elements of said stopping means being illustrated in the drawings and comprising a pair of rods 69^a connected by one or more levers to a rock shaft 69^b, and lugs or other devices 69^c on the rods 69^a disposed in the path of movement of the elevating device or platform 20. As these means are described and claimed in and forms the subject-matter of a co-pending application Ser. No. 706,339, no claim is made herein to said stopping means. To those skilled in the art to which my invention relates, many modifications in construction and widely differing embodiments of the invention and applications thereof will suggest themselves without departing from the spirit and scope thereof. The descriptions and the disclosure herein

are purely illustrative and are not intended to be in any sense limiting.

What I claim is:

1. In a truck, the combination with a frame and wheels therefor, of a pair of relatively movable members, one of said members including a pair of vertical guides mounted on said frame and the other member comprising an elevating device slidably mounted in said guides, a plurality of pairs of sheaves carried by said members, one pair being mounted on one of said members on an axis disposed midway between said guides and the other pairs being carried by the other member and disposed at opposite sides of and equal distances from said axis, a pair of drums carried by one of said members and disposed at opposite sides of and equal distances from said axis, means for rotating said drums, flexible hoisting members, each arranged to wind on and off one of said drums and engage one sheave of each pair thereof, and means for securing the free ends of said hoisting members to one of said relatively movable members. 70
2. In a truck, the combination with a frame and wheels therefor, of a pair of relatively movable members, one of said members including a vertical frame mounted on said frame and provided with guides and the other member comprising an elevating device slidably mounted in said guides, a plurality of pairs of sheaves carried by said members, one of said pairs of sheaves being mounted on said guide frame on an axis disposed midway between said guides, a pair of drums carried by one of said members and disposed at opposite sides of and equal distances from said axis, means for rotating said drums, flexible elevating members, each arranged to wind on and off one of said drums and engage one sheave of each pair thereof, and means for securing the free ends of said hoisting members to one of said relatively movable members. 75
3. In a truck, the combination with a frame and wheels therefor, of a vertical frame constituting guides, mounted on said first mentioned frame, an elevating device slidably mounted in said guides, a plurality of pairs of sheaves carried by said vertical frame and elevating device, one of said pairs of sheaves being mounted on said guide frame on an axis disposed midway between the guides, a pair of drums carried by one of said members and disposed at opposite sides of and equal distances from said axis, means for rotating said drums, flexible hoisting members, each arranged to wind on and off one of said drums and engage one sheave of each pair thereof, and means for securing the free ends of said hoisting members to one of said relatively movable members. 80
4. In a truck, the combination with a frame and wheels therefor, of a pair of relatively movable members, one of said members including a vertical frame mounted on said first mentioned frame and provided with guides and the other member comprising an elevating device slidably mounted in said guides, pairs of sheaves carried by each of said members and disposed at opposite sides of and equal distances from a point midway between said guides, a separate pair of sheaves mounted on one of said members on an axis disposed midway between said guides, a pair of drums carried by one of said members and disposed at opposite sides of and equal distances from the axis of said separate pair of sheaves, means for rotating said drums, flexible hoisting members, each arranged to wind on and off one of said drums at one end and to engage one sheave of each said pair thereof, and means for operatively connecting the opposite ends of said flexible members to one of said relatively movable members. 90
5. In a truck, the combination with a frame and wheels therefor, of a vertical frame constituting guides, mounted on said first mentioned frame, an elevating device slidably mounted in said guides, a plurality of pairs of sheaves carried by said vertical frame and said device, one pair of said sheaves being mounted on said guide frame on an axis disposed midway between the guides, a pair of drums carried by said first mentioned frame and disposed at opposite sides of and equal distances from the axis of the pair of sheaves on said guide frame, means for rotating said drums, an equalizing element secured to said guide frame, 100 flexible hoisting members, each arranged to wind on and off one of said drums and engage one sheave of each pair thereof, and means for securing the free ends of said hoisting members to the ends of said equalizing element. 105
6. In a truck, the combination with a frame and wheels therefor, of a pair of relatively movable members, one of said members including a pair of vertical guides mounted on said frame and the other member comprising an elevating device slidably mounted in said guides, a plurality of pairs of sheaves carried by said relatively movable members, one pair of said sheaves being mounted on one of said members on an axis disposed midway between said guides, a pair of drums carried by one of said members and disposed at opposite sides of and equal distances from said axis, means for rotating said drums, an equalizing element pivoted intermediate its ends on an axis disposed midway between said guides, and a flexible hoisting member arranged to wind on and off each of said drums and engage 120
- 65

- one sheave of each pair thereof, the free end of each said hoisting member being secured to that end of the equalizing element remote from the drum on which it winds.
5. 7. In a truck, the combination with a frame and wheels therefor, of a vertical frame mounted on said first mentioned frame and provided with guides, an elevating device slidably mounted in said guides, 10 an equalizing device movably mounted on one of said frames in a plane midway between said guides, a pair of driven elements carried by said first mentioned frame and disposed at opposite sides of and equal distances from the plane midway between said guides, a pair of flexible hoisting members, each arranged to engage one of said driven elements at one end and operatively connected at its opposite end to said equalizing 15 device, and a plurality of rotatable elements carried by said vertical frame and said elevating device over which said hoisting members run.
8. In a truck, the combination with a frame and wheels for said frame, of a pair of vertical guides mounted on said frame, a battery on said frame in spaced relation to said guides, an elevating device slidably engaging said guides, a motor and power 20 transmitting means supported between said battery and said guides, a pair of drums connected to and disposed at opposite sides of said power transmitting means, and mechanism for raising and lowering said 25 elevating device, said mechanism including sheaves supported upon said guides and flexible members engaging said sheaves and elevating device and arranged to wind on and off said drums.
40. 9. In a truck, the combination with a frame and wheels for said frame, of a guide frame vertically supported on said frame, an elevating device slidably engaging said guide frame, pairs of sheaves mounted on said 45 guide frame and elevating device, a separate pair of sheaves disposed intermediate the pairs of sheaves on said guide frame, a pair of drums mounted on said frame, flexible members each engaging one sheave of each 50 pair and arranged to wind on and off one of said drums at one end, means for securing the opposite end of each of said flexible
- members to one of said frames, and means for rotating said drums.
10. In a truck, the combination with a frame and wheels therefor, of a guide frame on said frame, an elevating device slidably engaging the guides in said guide frame, a pair of spaced sheaves carried by said guide frame, a pair of spaced sheaves carried by 60 said elevating device, a pair of sheaves on said guide frame intermediate the spaced sheaves thereon, a pair of drums, flexible hoisting means running around corresponding sheaves of said pairs of sheaves and said 65 intermediate sheaves and arranged to wind on and off said drums, and means for rotating said drums.
11. In a truck, the combination with a frame and wheels therefor, of a guide frame 70 on said frame, an elevating device slidably engaging the guides in said guide frame, a pair of spaced sheaves carried by said guide frame, a pair of spaced sheaves carried by 75 said elevating device, a pair of sheaves on said guide frame intermediate the spaced sheaves thereon, a pair of drums, flexible hoisting members running around corresponding sheaves of said pairs of sheaves and said intermediate sheaves and arranged 80 to wind on and off said drums at one end, means for rotating said drums, and an equalizing member to which the free ends of said flexible members are connected.
12. In a truck, the combination with a frame, wheels for said frame and means for driving certain of said wheels, of a guide frame on said frame, a motor and a power means on said frame, a pair of drums driven by said power means, an elevating device 90 slidably engaging said guide frame, spaced pairs of sheaves carried at the upper end of said guide frame on a transverse axis, a pair of spaced sheaves on said elevating device, guiding means on one of said frames 95 arranged substantially in a plane between said pairs of sheaves, and flexible members arranged to wind on and off said drums and engaging said sheaves and said guiding means.

In testimony whereof, I have hereunto subscribed my name.

EDWARD H. REMDE,
